UNITED STATES PATENT OFFICE.

PATRICK J. MORONEY, OF PHILADELPHIA, PENNSYLVANIA.

CAP-SPINNING MACHINE.

977,323.

Specification of Letters Patent. Patented Nov. 29, 1910.

Application filed September 27, 1909. Serial No. 519,826.

To all whom it may concern:

Be it known that I, PATRICK J. MORONEY, a subject of the King of Great Britain and Ireland, residing in Philadelphia, Pennsylvania, have invented certain Improvements in Cap-Spinning Machines, of which the following is a specification.

The main object of my invention is to so construct a cap spinning machine that the spindles can be placed in operative position close to the draft rolls, so that a comparatively short staple fiber can be spun, as well as fiber of long staple.

A further object of the invention is to so construct the machine that the entire upper spindle rail carrying the spindles and caps can be lowered so as to allow for the doffing of the caps and bobbins without interfering with the draft rolls.

20 In the accompanying drawings:—Figure 1, is a front view of sufficient of a cap spinning machine to illustrate my invention, the spindles being raised; Fig. 2, is a sectional view on the line 2—2, Fig. 1; Fig. 3, is a 25 view similar to Fig. 1, with the upper spindle rail lowered; and Fig. 4, is a sectional view on the line 4—4, Fig. 3.

A is the frame of the spinning machine, B is the lower spindle rail rigidly secured to 30 the end frames A'.

C is the upper spindle rail and c is the lifter plate. The ends of the rails C are adapted to vertical grooves a in the frames A'.

35 D, D are the spindles mounted in the usual manner and having the usual form of caps d.

E is the front bottom draft roll and E' is the front top draft roll mounted so as to be 40 located above the caps when in the raised position, as shown in Figs. 1 and 2, but so located that when the spindle rail is lowered with the spindle and caps there will be sufficient space to allow for the ready removal of 45 the caps.

F is the guide rail having arms f provided with eyes through which the yarn passes. These arms are preferably pivoted to the rail at f', so that they can be turned to one 50 side out of line with the caps to allow for the ready removal of the caps.

The upper spindle rail C may be raised and lowered in any manner desired. In the present instance I use two toggle links b, b', 55 one set of links being pivoted to the rail C and the other set of links pivoted to the rail

B and both links being pivoted to a connecting rod H at h. At the end is a rod H', pivoted to the last toggle and connected to the short arm i is an operating lever I. This operating lever is pivoted at i' and has a handle i² and a locking bolt i³ of the ordinary type. The bolt is adapted to notches in a segment I' secured to the frame of the machine so that the lever I can be locked in either of its two positions. Other means for locking the lever may be resorted to without departing from the essential features of the invention.

In order to counterbalance the rail C and its spindles, I use one or more counterbalance levers K which are pivoted at k to brackets K' secured to the fixed rail B. One arm of the counterbalance lever rests against the end of a post L secured to the rail C, and 75 on the other end of the lever is an adjustable weight k', thus the rail C is counterbalanced and can be freely raised and lowered.

The operation is as follows:—When the 80 spinning frame is running the rail C is in the raised position, as illustrated in Fig. 1, and the caps are comparatively close to the nip of the front rollers. In some instances they may be within three and one-half 85 inches, or even less, according to the design of the machine. The rail C is held in its raised position by the locked toggle mechanism described above.

When the bobbins are full the frame is 90 stopped and the rail C is lowered by operating the lever I. The movement of the rail C is about equal to the traverse of the bobbins. This will bring the upper ends of the caps a sufficient distance below the bite of 95 the rolls E, E', so as to allow for the ready removal of the caps and the doffing of the spindles. In the event of the guides f being in the way, these guides can be turned on the pivots out of line with the caps. When the 100 bobbins are placed on the spindles and the caps adjusted in position, then the rail C is again moved to the raised position and locked.

By the above construction it will be seen 105 that I am enabled to spin yarn of a comparatively short staple as well as long staple yarn.

I claim:—

1. The combination in a spinning machine, of draft rollers, a lifter plate, bobbins mounted thereon, a spindle rail, spindles

mounted thereon and slideable through the said lifter plate and bobbins, caps mounted on the spindles and arranged to envelop the bobbins to feed yarn thereto, with means for lowering the spindle rail.

2. The combination in a cap spinning machine, of draft rollers, a lifter plate, bobbins mounted thereon, a spindle rail, spindles fixed thereon and slideable through the lifter plate and the bobbins, caps mounted on the spindles and arranged to envelop the bobbins, the said lifter plate being capable of vertical movement during the winding of the bobbins, and means for raising and lowering the spindle rail.

3. The combination in a cap spinning machine, of the supporting structure, draft rollers, a lifter plate, bobbins rotatably mounted thereon, said lifter plate being capable of vertical movement, a movable spindle rail, spindles mounted thereon, a fixed rail, a toggle joint connecting the fixed rail and the spindle rail, a hand lever pivoted on the supporting structure, and a link connecting the hand lever to the toggle joint.

4. The combination in a cap spinning machine, of the supporting structure, draft rollers, a lifter plate, bobbins rotatably

mounted thereon, a movable spindle rail, spindles mounted thereon, a fixed rail, a toggle joint connecting the fixed rail and the spindle rail, a hand lever pivoted to the supporting structure, a link connecting the hand lever to the toggle joint, and a counter-balance for the spindle rail.

5. The combination in a cap spinning machine, of the supporting structure, draft rollers, a lifter plate, bobbins rotatably mounted thereon, a movable spindle rail, spindles mounted thereon, a fixed rail, a toggle joint connecting the fixed rail and the spindle rail, a hand lever pivoted to the supporting structure, a link connecting the hand lever to the toggle joint, and a counter-balance for the spindle rail, with means on said hand lever for automatically locking the spindle rail in its upper and lower positions.

In testimony whereof, I have signed my name to this specification, in the presence of two subscribing witnesses.

PATRICK J. MORONEY.
